AIR CONDITIONING APPARATUS

Robert R. Candor, Dayton, Ohio, assignor to General Motors Corporation, Dayton, Ohio, a corporation of Delaware

Application July 24, 1937, Serial No. 155,534

6 Claims. (Cl. 257—3)

This invention relates to refrigerating apparatus and more particularly to a refrigerating apparatus which may also be used for heating purposes.

It is an object of this invention to provide a method and an apparatus for maintaining the temperature of a given space substantially constant irrespective of the temperature of the atmosphere.

Another object of this invention is to provide an air conditioning system in which waste heat of compression is utilized.

A further object of this invention is to provide a new and improved control system.

Still another object of this invention is to provide an outside psychrometric device which modifies the action of an inside psychrometric device so as to increase the amount of heat supplied in the winter as the outside temperature decreases and to increase the amount of cooling in the summer as the outdoor temperature increases.

It is another object of this invention to provide means for dehumidifying the air when the humidity becomes too high even though the effective temperature is comfortable, and to provide means for adding moisture to the air when the humidity becomes too low.

Further objects and advantages of the present invention will be apparent from the following description, reference being had to the accompanying drawings, wherein a preferred form of the present invention is clearly shown.

In the drawings:

Fig. 1 is a diagrammatic showing of my air conditioning apparatus with the valve set for cooling;

Fig. 2 is a diagrammatic view of the same apparatus shown in Fig. 1 with the valve set for heating;

Fig. 3 is a diagrammatic view showing the control mechanism which may be used for changing over from heating to cooling and vice versa;

Fig. 4 is a diagrammatic view showing the electrical circuit which may be used in my system.

Referring now to Fig. 1 of the drawings, I have shown an enclosure 10 provided with my conditioning apparatus. In this figure the apparatus is shown set for cooling the room during the summer season. A heat exchange unit 12 is

mounted within the conditioning chamber 14 and provided with an inlet 16 and an outlet 18.

An internal combustion engine 20 is provided for driving the compressor 22. The compressor dis-

charges compressed refrigerant into a receiver 24. The condenser 24 is provided with a cooling jacket 26. Water is supplied to the cooling jacket 26 through pipe 28 and is discharged through the outlet 30. The amount of water supplied to the condenser is regulated by the valve 32 which is controlled in response to pressure within the pipe line 34 which conveys the compressed refrigerant to the condenser.

When the apparatus is set for cooling, compressed refrigerant leaves the compressor via the pipe 36 which leads to the three-way valve 38. This valve is set so as to discharge the compressed refrigerant into pipe 40 which leads to the three-way valve 42 which in turn is set to discharge into the pipe 34 leading to the condenser. The liquid refrigerant leaves the condenser 24 via the pipe 44 which leads to the three-way valve 45. The three-way valve 45 is set to discharge into the pipe 46 which leads to the three-way valve 48. The three-way valve 48 being set so as to discharge into the pipe line 16 leading to the heat exchange coil 12. The valve 50 placed in line 16 is a thermostatic expansion valve which automatically opens to admit additional refrigerant into the heat exchange coil 12 when the pressure within the coil 12 falls below a predetermined amount. This expansion valve is provided with a thermostatic means 51 which automatically throttles the valve when the refrigeration effect reaches the return line 18.

Whenever the system is used for cooling purposes the refrigerant is required to pass through the thermostatic expansion valve 50. A by-pass line 52 is provided around the thermostatic expansion valve 50. This by-pass is provided with a solenoid valve 54 which automatically opens when changing over from summer to winter operating conditions. The return line 18 leads to a three-way valve 56 which is set to discharge into the pipe line 58 leading to the three-way valve 60 which, during summer conditions, is set to deliver the refrigerant vapor into the line 62 leading to the intake of the compressor.

In order to dissipate the heat generated by the internal combustion engine and the compressor, a water jacket 64 has been provided around the internal combustion engine and a water jacket 66 has been provided around the compressor 22. Cooling water is supplied to the jackets 64 and 66 through the pipe line 68. The heated water leaves the jackets 64 and 66 through the pipe 70 which leads to the three-way valve 72. Three-way valve 72 may be set as shown in Fig. 1 to convey the water into pipe 74 which is connected with pipe 76 leading to a water tank 78 which

is provided with a discharge pipe 80 through which the water is finally discharged from the system. The three-way valve 72, as will be explained hereinafter, may be set so as to convey the hot water coming through the pipe 70 through a heating coil 82 located in the conditioning chamber 14.

A fan 84 is provided for circulating air through the conditioning compartment 14. The compartment 14, it will be noted is provided with a partition member 86 which divides the conditioning chamber into two separate passages. Butterfly dampers 88, 89, and 90 are provided for controlling the flow of air through the conditioning compartment. As shown in Fig. 1, the damper 88 is set so as to cause all of the air flowing through the apparatus to flow over the heat exchange coil 12, and the dampers 89 and 90 are set so as to cause all of the air to also flow over the coil 82 which may or may not reheat the air depending upon the setting of the valve 72 as will be explained hereinafter. The exhaust from the internal combustion engine is caused to pass through the exhaust pipe 92 into the exhaust tank 94 which is provided with a muffled outlet 96.

Whenever it is desired to cool air for the compartment 10, the internal combustion engine is caused to operate thereby compressing the refrigerant by means of the compressor 22 which discharges the compressed refrigerant into the condenser 24. The refrigerant is condensed in the condenser 24 and is forced upwardly through the pipes 44, 46, and 16 into the heat exchange coil 12 which under these conditions acts as an evaporator cooling coil to cool the air circulated over the coil by means of the fan 84. The evaporated refrigerant leaving the coil 12 is conveyed through the pipes 18, 58, and 62 back to the compressor.

The air passing over the cooling coil 12 will deposit a certain amount of moisture on the coil 12 with the result that the air leaving the apparatus will have its relative humidity lowered. Whenever it is desirable to lower the humidity without lowering the temperature of the air, the three-way valve 72 may be set so as to convey the hot water leaving the cooling jackets 64 and 66 through the heating coil 82 with the result that the air passing through the conditioning chamber 14 will be reheated an appreciable amount. All of the three-way valves and the butterfly valve may be manually controlled so as to change over from cooling in the summertime to heating in the wintertime or, as will be explained hereinafter, automatic means may be provided for changing over from cooling to heating. The three-way valve 72 may be manually controlled or it may be controlled automatically in a manner to be explained hereinafter. When it is desired to change over from cooling in the summertime to heating in the winter, the valves 38, 42, 45, 48, 56, 60, and 72 are all adjusted to the position shown in Fig. 2. The butterfly valves are all adjusted to the position shown in Fig. 2 so that the air flowing through the conditioning apparatus flows over the coils 12 and 82 in parallel. In the case of manual adjustment, the butterfly valves may, of course, be set so as to cause the air to flow over only one of the coils or to flow over both of the coils in series as shown in Fig. 1.

With the apparatus functioning as a heating system, the supply of water for the receiver 24 is shut off and the refrigerant leaving the compressor flows through the pipe 36; valve 38; pipe 98; valve 48; pipe 16; by-pass pipe 52; valve 54; heat ex-

change coil 12, which under these conditions acts as a condenser for the refrigerant; pipe 18; valve 56; pipe 100; valve 42; pipe 34; receiver 24; pipe 44; valve 45; pipe 102; expansion valve 104; coil 106, which under these conditions acts as an evaporator; coil 108, which also serves to evaporate the refrigerant; pipe 110; valve 60; and, finally, pipe 62, which returns the vaporized refrigerant to the compressor 22. With this arrangement the cycle has been reversed, and the heat exchange coil 12, in place of serving as an evaporator, serves as a condenser with the result that air flowing over the coil is heated and the condensed refrigerant is evaporated in the coils 106 and 108.

A considerable amount of heat is dissipated by the internal combustion engine and the compressor; so, in order to utilize this heat, I have provided means for dissipating this heat into the air for the enclosure 10. Water is supplied through the feed lines 68 to the water jackets 64 and 66 of the internal combustion engine and compressor respectively, and the heated water leaving the jackets 64 and 66 is caused to circulate through the pipe 10; valve 72; heating coil 82; hot water tank 78, where it serves to give up heat to the evaporator coil 106 before being discharged through the outlet 80. In order to utilize the heat ordinarily lost in the hot exhaust from the engine, I place the one section of evaporator coil 108 in an exhaust tank 94 so that the hot exhaust gases may be used in evaporating refrigerant with the result that the heat dissipated by the internal combustion engine is fully utilized in heating the air for the enclosure. A throttling valve 112 is placed in the inlet 68 and is provided with a thermostatic bulb 114 placed adjacent the outlet pipe 80 so as to control the flow of cooling fluid through the system. In this manner only the necessary amount of cooling fluid is permitted to flow through the cooling jackets.

During the winter season it may be necessary to add moisture to the air for the room and, with this in mind, I have provided a spray head 116 for spraying water over the heat exchange coil 12 whenever humidity conditions within the enclosure require the addition of moisture to the air.

As explained hereinabove, all of the control valves may be manually operated so as to change from heating to cooling or vice versa. However, in a system of this type it is necessary that the large majority of the valves all be shifted at the same time or nearly at the same time so as to provide the proper flow lines for the refrigerant. I have provided automatic means, as shown in Fig. 3, for changing the settings of various valves whenever conditions within the room necessitate the change from heating to cooling or vice versa. I have also provided a novel control system for starting and stopping the internal combustion engine and controlling the capacity of the system in response to changes in conditioning requirements.

Fig. 3 diagrammatically shows the apparatus employed for changing over from heating to cooling or vice versa. This apparatus comprises a psychrometric device 118, to be explained more fully hereinafter, which has a movable contact 120, a stationary contact 122, and another stationary contact 124. The apparatus in Fig. 3 is shown set for winter operation. When heating is no longer required, and it becomes desirable to cool air for the enclosure, the movable contact 120 will move over into engagement with the sta-

tionary contact 124. When this takes place current will flow from the main line 126 through the contacts 120 and 124 through the line 128, stationary contact 130, movable contact 132, line 134, solenoid 136, to the main line 138.

Energization of the solenoid 136 causes the armature 140 to be moved to the left. Movement of the armature 140 to the left causes the contact arm 142 to engage the contact 144. It will be noted that the contact 142 is biased into engagement with the contact 144 by means of the spring 146 and that the armature 140 is biased to the right by means of a spring 148. When contact 142 engages 144 a circuit is closed which includes the control motor 150 and the battery 152. Closing of this circuit initiates operation of the motor.

The motor drives a shaft diagrammatically represented by the dotted lines 154, 156, and 158. The shaft 156 carries a resetting pawl 160 which cams the contact 142 out of engagement with the contact 144 after the shaft has made one half of a revolution. Opening the contacts 144 and 142 stops the motor 150. After the resetting pawl 160 has cammed the contact 142 downwardly, the contact 142 is engaged by the pawl 162 carried by the armature 140 and is held out of engagement. The one-half revolution of the shaft 156 causes the movable contact arm 132 to move out of engagement with the contact 130 and into engagement with the contact 164.

Once during each one-half revolution of the shaft 156, the movable contact 166 which is carried by the shaft 156 sweeps one contact segment 168 with the result that a circuit is closed from the main line 126, through the conductor 170, motors 171, 172 and 173, contact segment 168, contact 166, and the main line 138. The motors 171, 172 and 173 are the motors which automatically operate the butterfly dampers 88, 89 and 90 respectively. When current flows through line 169 the damper motors operate in one direction, and when current flows through line 171 the damper motors operate in the reverse direction. During the operation of the motor 150, the shaft 154 has also caused the operating rod 176 to have moved downwardly sufficiently so as to have rotated all of the three-way valves from the winter position to the summer position. The rod 176 cooperates with a plurality of operators 178 for the various valves, the arrangement being such that half a revolution of the shaft 154 turns each valve one quarter of a turn. The rod 176 carries on its upper end a movable contact bridging member 180 which engages contacts 190 and 192 during winter operating conditions and engages contacts 194 and 196 during summer operating conditions.

In changing over from summer to winter the contact 120 moves into engagement with the contact 122 with the result that a circuit is closed from the main line 126 through the contacts 120 and 122, the contact 164, movable contact 132, solenoid 136 to the main line 138. Energization of the solenoid 136 trips the movable contact arm 142 so that the motor circuit is again closed with the result that the valves etc., will be set for heating the room. After the motor 150 has made the necessary shift over, the resetting cam 160 again cams the movable contact 140 into the latched position.

Referring now to Fig. 4, it will be noted that the psychrometric device 118 comprises a main support 200 of insulation which carries on its face two sets of contact members—the one set

being provided for controlling the system during summer conditions and the other set being provided for controlling the system during winter conditions. The support 200 is mounted for horizontal movement. A spring 202 biases the support to the left, and an outside psychrometric device 228 biases the support to the right.

The movable contact 120 is pivotally mounted on a stationary pivot 222. The movable contact 120 may be operated by a dry bulb thermostat, a wet bulb thermostat, a combination of the two, or preferably by an effective temperature responsive means. A similar effective temperature responsive device may be used for imparting pivotal movement to the arm 224 of the outside psychrometric device 228. Directly above the device 228 there is provided a stationary pivot 230 on which is pivotally mounted a lever 232. The arrangement is such that pivotal movement of the arm 224 causes pivotal movement of the lever 232. As the outdoor effective temperature decreases the arm 224 tends to move to the left, and as the outside effective temperature increases the arm 224 tends to move to the right.

25 Pull rods 234 and 236 connect the movable support 200 to the arms 224 and 232 respectively. The arrangement is such that when the outdoor temperature exceeds a predetermined high the lever 224, through the pull rod 234, will shift the support 200 to the right in accordance with the increase in temperature; and when the temperature reaches a predetermined low the lever 232, through the pull rod 236 will, likewise, shift the movable support 200 to the right. The effect 30 of the movement of the support 200 to the right, during winter operating conditions, is to increase the capacity of the heating equipment so as to compensate for the colder walls, etc. Under summer conditions, the effect of movement of the support 200 to the right will be to maintain the inside effective temperature slightly higher with the result that the change noticed when one leaves or enters the room will not be much greater at higher temperatures than at lower temperatures.

35 Still referring to Fig. 4 which shows the circuit under winter conditions, it will be noted that the movable contact 120 is in engagement with a contact 238 which is in circuit with the solenoid valve 54 which controls the by-pass of refrigerant around the thermostatic expansion valve 50. The movable contact 120 is also in engagement with a contact segment 242 which closes a circuit through a solenoid 244. Energization of the 40 solenoid 244 closes the switch 246 which completes a circuit from the main line 240 to the ignition system 248 of the internal combustion engine and the starter 250.

The arrangement is such that when the engine starts and attains a predetermined speed, the speed responsive switch 252 opens the circuit through the starter mechanism 250 and closes this circuit through the solenoid valve 254 which automatically turns on the supply of cooling fluid for the engine and compressing cooling jackets. In order to be able to increase the engine speed as the load on the conditioning apparatus increases, the main control switch is provided with a shorter contact segment 256 so that, as the movable contact 120 moves into engagement with the segment 256, a circuit will be closed through the solenoid 258 which controls the engine throttle with the result that the speed of the engine will be increased.

45 Still further movement of the movable contact

120 in response to a further decrease in the temperature will cause the contact 120 to engage a stationary contact 260 which closes a circuit through a solenoid 262 which is instrumental in still further increasing the speed of the internal combustion engine. As the temperature within the room increases, the contact 120 will start moving to the right with the result that as it leaves the contact 260 the speed of the engine will be reduced, and as it leaves the contact segment 256 the speed of the engine will be further reduced, and as the movable contact leaves the contact segments 238 and 240 the ignition for the engine will be turned off, the cooling water will be shut off at 254 and the valve 54 will be closed.

If the temperature within the room continues to increase to such an extent that cooling becomes necessary, the contact arm 120 will move into engagement with the contact 124 with the result that the equipment will be reset for cooling purposes as explained hereinabove. The arrangement is such that when the contact 120 engages the contact 124 it also engages the contact segment 264 which closes a circuit through the solenoid valve 266 which turns on the cooling water for the condenser 24. The arm 120 simultaneously engages with another contact segment 268 which closes a circuit through the solenoid 244 for operating the switch 246 which starts the conditioning apparatus into operation. Contacts 270 and 272 corresponding to contacts 256 and 260 have been provided for increasing the speed of the engine as the conditioning load increases due to further rise in temperature.

In order to provide for humidity control a 35 humidistat 274 has been provided which is in series circuit relationship with the valve 276 which turns on the water to the spray head 116 when the humidity becomes too low. The humidistat 274 and solenoid valve 276 are in series with the contacts 180, 190, and 192 with the result that the valve 276 will always remain closed during summer operating conditions due to the fact that the contact 180 will be out of engagement with the contacts 190 and 192 during summer operating conditions.

There may be times when the effective temperature within the enclosure may be satisfactory but the relative humidity may be excessively high. Under these conditions the humidistat 280 will close the circuit leading from the main line 240 through the solenoid 282 to the main line 239. Energization of the solenoid 282 starts up the cooling equipment but, at the same time that the solenoid 282 is energized, a branch circuit through the operating motor 284 is closed which automatically adjusts the three-way valve 72 so as to reheat the air leaving the heat exchange coil 12. In order to prevent reheating from taking place when the indoor temperature is high, a solenoid operated switch 286 has been provided in series with the humidity responsive device 280.

The solenoid operated switch 286 is biased into the closed position but is held open whenever the movable contact 120 is in engagement with the contact segment 270. The motor 83 which operates the fan 84 is connected directly across the main lines 239 and 240 at all times so that the air will be circulated during all seasons of the year except at such times when the manually operated switch 290 is open. Opening of the switch 290, it will be observed, completely closes down the entire air conditioning system.

While the form of embodiment of the inven-

tion as herein disclosed, constitutes a preferred form, it is to be understood that other forms might be adopted, all coming within the scope of the claims which follow.

5 What is claimed is as follows:

1. In combination, a reversible refrigerating system, an internal combustion engine drive for said system, indoor temperature responsive means for increasing the speed of said engine as the temperature goes either above or below a predetermined range, and means responsive to the outdoor temperature modifying the action of said indoor temperature responsive means so as to raise said temperature range as the outdoor temperature either decreases or increases beyond a predetermined value.

2. In combination, a refrigerant condensing means in thermal exchange relationship with air to be conditioned, refrigerant evaporating means, refrigerant compressing means, refrigerant flow connections between said condensing means, evaporating means and said compressing means, means for controlling the flow of refrigerant through said connections, an air heating coil in thermal exchange relationship with air to be conditioned, compressor operating means, means for flowing a heat transfer medium in thermal exchange relationship with said compressor operating means, means for thereafter flowing said medium through said air heating coil, and means for flowing the heat transfer medium leaving said air heating coil into thermal exchange relationship with said evaporating means.

3. In combination, a refrigerant condensing means in thermal exchange relationship with air to be conditioned, refrigerant evaporating means, refrigerant compressing means, refrigerant flow connections between said condensing means, evaporating means and said compressing means, means for controlling the flow of refrigerant through said connections, an air heating coil in thermal exchange relationship with air to be conditioned, compressor operating means, means for flowing a heat transfer medium in thermal exchange relationship with said compressor operating means, means for thereafter flowing said medium through said air heating coil, means for flowing the heat transfer medium leaving said air heating coil into thermal exchange relationship with said evaporating means, and means for increasing the load on said compressor operating means in response to an increase in the heating requirements.

55 4. Conditioning apparatus for an enclosure comprising in combination, a first heat exchange unit in thermal exchange relationship with a medium to be attemperated, a compressor, an internal combustion engine for operating said compressor, a second heat exchange unit in fluid flow relationship with said first unit and said compressor, temperature responsive means for increasing the speed of said engine in response to a decrease in temperature, and means using 60 waste heat from said internal combustion engine for heating said medium and for thereafter heating said second heat exchange unit.

5. In combination, a refrigerant condensing unit in thermal exchange relationship with air to be heated, a compressor, a heat exchange unit in fluid flow relationship with said refrigerant condensing unit and said compressor, an auxiliary heat exchange unit, means for reversing the functions of said condensing unit and said 70 first named heat exchange unit, means for con-

necting said auxiliary heat exchange unit in series refrigerant flow relationship with said compressor, said condensing unit and said heat exchange unit in response to changes in temperature of said air, compressor operating means, and means utilizing waste heat generated by said compressor operating means for heating said auxiliary heat exchange unit.

6. In combination, a reversible refrigerating system including a compressor, indoor tempera- 10

ture responsive means for increasing the speed of said compressor as the temperature goes either above or below a predetermined range, and means responsive to the outdoor temperature modifying the action of said indoor temperature responsive means so as to raise said temperature range as the outdoor temperature either decreases or increases beyond a predetermined value.

ROBERT R. CANDOR.
